US00D672480S

(12) **United States Design Patent**
Maxik et al.

(10) **Patent No.:** US D672,480 S
(45) **Date of Patent:** ** Dec. 11, 2012

(54) **LUMINAIRE**

(75) Inventors: **Freddie S. Maxik**, Indialantic, FL (US);
David Henderson, Indialantic, FL (US);
Mark Penley Boomgaarden, Indian
Harbour Beach, FL (US); **Addy S.**
Widjaja, Palm Bay, FL (US); **Emilio**
Flores, Indian Harbor, FL (US); **Shane**
Sullivan, Indialantic, FL (US); **Wei Sun**,
Davie, FL (US)

(73) Assignee: **Lighting Science Group Corporation**,
Satellite Beach, FL (US)

(**) Term: **14 Years**

(21) Appl. No.: **29/416,782**

(22) Filed: **Mar. 27, 2012**

Related U.S. Application Data

(62) Division of application No. 29/360,983, filed on May
4, 2010, now Pat. No. Des. 658,791.

(51) **LOC (9) Cl.** **26-04**

(52) **U.S. Cl.** **D26/2**

(57) **CLAIM**

We claim, the ornamental design for a luminaire, as shown and described.

DESCRIPTION

FIG. 1 is a side plan view of a first embodiment of the invention;

FIG. 2 is a top plan view of the embodiment of FIG. 1;

FIG. 3 is a bottom plan view of the embodiment of FIG. 1;

FIG. 4 is a first perspective view of the embodiment of FIG. 1; and,

FIG. 5 is a second perspective view of the embodiment of FIG. 1.

The broken line showing of top and bottom of the bulb is included for the purpose of illustrating only and forms no part of the claimed design.

1 Claim, 5 Drawing Sheets
